Gideon Fleetships. 9696X

394

The Schedule referred to in these Statute Rules and making part of this same containing a description in the words of the said Gideon Fleetships, briefly of his improvement in the art of propelling or driving boats or other water-crafts. To all whom these Presents shall come, Be it known that Gideon Fleetships of Fleet have invented a new and useful improvement in the art of propelling or driving boats or vessels on the water-crafts in shoal or swift water in Rivers and Canals, or other waters. The following is a full and exact description thereof. It consists of a Pedestrian traction or pulley, propelling, or propelling and driving wheel or wheels, which by receding and rolling on the bottom of a River, Canal or other water of sufficient depth to carry boats will draw or propel them where they cannot be taken with paddle-props. Said boat may be taken in the usual way, ^{with} ~~in~~ shape or sign to said boat's name or forsooth. Said wheel may be placed before or behind or between or right through the bottom, or on either or both sides, or in all said places in said boat and toll or travel on a bed of stones in Canal or other water or a rail or rails placed on the bottom or side of a Canal or other water, said wheel may be made of cast or wrought iron or of wood, or partly of these and partly of iron, of such diameter as to suit the general depth of water so that the shaft or arbor shall be proportionately above water and of sufficient strength to bear force with the size of the boat. The rim or periphery to be so formed neither open or projecting when it is to run on the gravel, stones or plants at the bottom of Rivers, Canals or other waters or on their sides or top.

or if it is to run as a rail on the side of, bottom of
 river banks or other places to be formed so as to correspond
 with the form of the rail whether it be made angular or straight
 out, with a projection or flanges or plates on each
 side, so as to make the wheel follow the rail similar to
 those on steam carriages to run on rail roads. The
 shaft or axle to be about one fourth of the diameter of the
 wheel in length, with flanges or castings or
 iron to keep the frame together. The frame to be made
 with two arms, one fourth greater in length than
 the diameter of the pedestrian wheel, with two posts
 placed on the side, so as to project one foot off the
 diameter of the wheel below, cast to project above so as
 to clear the wheel with a gap on the top to correspond
 with the length of the shaft of the pedestrian wheel.
 In the lower end of the post, the wheel is hung, the other end of the
 arms being turned to about two thirds of the diameter of the
 wheel and strongly braced to keep it from rocking or mov-
 ing and fastened to the boat by braces or pins to do as to keep
 the wheel in nearly a vertical position and permit it to rise
 and fall in an opening between two boats or through the boat
 so that it may roll on the bottom or rail at different parts of the
 water, when steady, when on propell the boat or boat forward.
 This wheel may be raised, when, if pulled down on the bottom
 or rail by pulleys and weights or by levers and pulleys or by
 spring. Said wheel may be fine and continued in motion
 by steam or any other power communicating to a wheel or
 on over the center of most of the wheel frames, and from
 that to the pedestrian wheel, by a coupling or ship chain
 running over a corresponding wheel for the action of the pedes-
 trian wheel in any of the forms of gears.
 When the usual rudder becomes insufficient to guide the boat
 by reason of short water, there there may be a wheel on the

middle placed in or near the stern of the boat which by facing it on the bottom in a proper position, will give the desired direction. Also the sides of the boat might provide with buoy-weights of wood or cast iron attached to beams which may be placed on the bottom when the water is too shallow and when the boat is to pass shoals and bars which it otherwise could not. In deep water paddle-wheels may be used as in other boats, moved by the same power that moves the pedestals, ^{which} and when not wanted may be raised out of the water. What I call as my own invention and not previously known in the above described manner, is this of raised pedestals, friction repulsion, for a wheel, on an anchor wheel, in giving my name to which is to be made to follow the bottom of rivers and canals or other waters of different depths, its adaptation in shape to rocks laid on the bottom of canals or other water so that it enabled to follow the track and run over a boat or boat or other water craft (as far as it differs from those used on steam carriages or cars) the lightning or recognition of said wheel, The wheel on a wooden and ^{metal} the buoy wheel and their use — Date 11. Wisconsin Co. 11
